CLAIM

The ornamental design for a hand held cosmetic device, as shown and described.

DESCRIPTION

FIG. 1 is a bottom, front, right side perspective view of a hand held cosmetic device according to my new design; FIG. 2 is a front elevation view thereof;

FIG. 3 is a rear elevation view thereof;

FIG. 4 is a left side elevation view thereof;

FIG. 5 is a right side elevation thereof;

FIG. 6 is a top plan view thereof; and,

FIG. 7 is a bottom plan view thereof.

The dot-dash broken lines represent boundaries of the claimed design and form no part of the claimed design. The dash-dot broken lines depict portions of the hand held cosmetic device that form no part of the claimed design.
